UNITED STATES PATENT OFFICE.

ELMER JACOB, OF NORTH ADAMS, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT UNWINDING OF YARN FROM BOBBINS.

Application filed September 10, 1927. Serial No. 218,769.

This invention relates to improvements in weft replenishing magazines for looms more particularly though not necessarily of the multicolor type, and it is a general object of 5 the invention to provide means to prevent the final winds on bobbins awaiting transfer from unwinding and becoming entangled.

In multicolor weft replenishing mechanisms of the type generally employed the 10 bobbins are arranged in vertical parallel stacks and there is a control device called a cradle located at the bottom of each stack. The end of filling from each bobbin is led through a slot in the magazine frame and 15 extends to a thread holder. During the normal operation of the loom the bobbins are vibrated due to the jar of the loom and the final winds of the yarn on the bobbins have a tendency to slip off and become entangled. 20 This is particularly true in the artificial yarns such as rayon where there is little natural adhesion of the coils of yarn one for the other. It is a further object of my invention to provide means connected to the 25 cradles which shall engage that part of the yarn adjacent the tips of the bobbins to prevent the final winds from working loose.

It is further found that the bobbins as 30 they await transfer are subject to a certain amount of wearing due to the vibration and relative movement of the bobbins with respect to each other. It is another object of my present invention to provide a device which will engage the bobbins and hold the 35 same against vibration so as to prevent the relative movement which causes said wearing of the filling.

With these and other objects in view which will appear as the description proceeds, my invention resides in the combination and arrangement of parts hereinafter described and set forth in the claims.

In the accompanying drawings wherein I have shown an embodiment of my invention, 45 Fig. 1 is a central vertical section through a multicolor magazine looking outwardly toward the tips of the bobbins.

Fig. 2 is a rear elevation looking in the direction of arrow 2, Fig. 1, and

Fig. 3 is a detailed horizontal section on 50 line 3—3 of Fig. 1.

Referring to the drawings the multicolor magazine includes in its construction an outside plate 10 provided with a plurality of vertical parallel grooves 11 which guide the 55 tips T of the bobbins B. Located adjacent the bottom of each groove is a cradle 12 the outer end of which is journaled as at 13 to the plate 10.

Under normal conditions the cradles are 60 so placed that the upper lip 14 thereof lies across the path which must be followed by the bobbins as they descend toward transfer position so that the bobbins of each stack will normally be located above the corresponding cradle. At the time of indication 65 of weft exhaustion the cradle of the stack corresponding to the active shuttle will be rocked about its axis so that the lip thereof will pass beyond the adjacent slot and the 70 stack of bobbins will fall. The lowermost bobbin will be caught on a run 15 of the cradle and held until the shuttle which gave the indication of weft exhaustion is again 75 to be picked to that side of the loom where the magazine is located, at which time the cradle will be rocked back to its normal position to release the lowermost bobbin and to support the others lying thereabove. The matter thus far described is of common construction and may be substantially the same 80 as shown in prior Patent No. 1,030,748 to Ryon. Reference may be had to said patent for the mechanism for operating the cradles.

As previously stated it is found that certain yarns are prone to unravel so that the final winds thereof which are on the conical part of the yarn adjacent the bobbin tips will slide away from the main body of the 85 yarn. In order to prevent the yarn from unwinding and also to release the bobbins so that they may fall without interruption at the time the cradle rocks I employ a plurality of flexible bobbin engaging elements, 90 one for each stack of bobbins. Inasmuch as the elements are all the same a description of one will suffice for all.

I provide each cradle with a stud 20 and

attach thereto the lower end of a flexible strap 21 the upper end of which is connected to a tension spring 22 held by means of screw 23 to the plate 10. The screw 23 and the corresponding stud 20 are so located that the strap 21 will normally extend parallel to and in engagement with the conical portions of the adjacent stack of bobbins as shown at the left hand side of Fig. 1. When in this position the strap 21 will conform itself to the shape of the bobbins of the corresponding stack and will act to prevent the last coils of yarn from unraveling.

At the time of indication of substantial weft exhaustion the cradle corresponding to the active shuttle will be rocked as previously described and the stud 20 thereof will be moved away from the stack of bobbins controlled by the cradle to some such a position as that indicated at M in Fig. 1. When in this position the strap is out of contact with the bobbins so that the latter are free to descend without interruption or interference on the part of said strap. The tension springs 22 are light and do not interfere in any way with the proper operation of the cradles. When the cradle returns to its normal position after the lowermost bobbin of the corresponding stack has been released the strap will be restored to its normal position in engagement with the conical portion of the yarn adjacent the tips of the bobbins.

From the foregoing it will be seen that I have provided a very simple means for engaging the conical portions of the yarn adjacent the tips of the bobbins to prevent the same from unraveling. It will further be seen that said means are placed under control of a part of the magazine which acts in timed relation with the indication of weft exhaustion. It will also be seen that the cradles or gates which release the lowermost bobbin of each stack are effective to move the restraining yarn engaging element out of contact with the bobbins at such times as the latter are called upon to move downwardly toward transfer position. It is obvious, also, that the engagement of the straps with the bobbins tends to prevent vibration of the latter and therefore to reduce the abrasion and wearing which results from the vibration of the bobbins.

Having thus described my invention it will be apparent that changes and modifications may be made therein by those skilled in the art without departing from the spirit and scope of the invention and I do not wish to be limited to the details herein disclosed, but what I claim is:

1. In a weft replenishing mechanism, means to guide a stack of bobbins which move toward transfer position by gravity, and flexible means resiliently mounted to en-

gage the conical portions of the yarn on the bobbins adjacent the tips of the bobbins to prevent the winds of yarn adjacent the tips from unwinding.

2. In a weft replenishing mechanism, means to guide a stack of bobbins, a cradle located at the bottom of the stack of bobbins, and means connected to and controlled by the cradle to engage those portions of the yarn on the bobbins adjacent the tips of the latter to prevent the final winds of yarn from unraveling.

3. In a weft replenishing mechanism, means to guide a stack of bobbins, releasing means located adjacent the bottom of the first named means to release the bobbins one at a time, said releasing means being rotatable about an axis, and an element connected to the releasing means and including a flexible member to have contact with those portions of the yarn adjacent the tips of the bobbins to prevent unraveling of the last winds of yarn adjacent the tips of bobbins.

4. In a weft replenishing mechanism having a frame, means to guide a stack of bobbins, a release cradle at the bottom of the stack of bobbins movable angularly to release the bobbins one at a time, a flexible bobbin engaging element operatively connected to the cradle and having contact with those portions of the yarn adjacent the tips of the bobbins, and resilient means interposed between the upper end of the element and the weft replenishing mechanism frame tending normally to hold said element against the bobbins.

5. In a weft replenishing mechanism, means defining guides for a stack of bobbins, a cradle located at the bottom of the stack of bobbins and mounted for angular movement, a flexible member secured to and moving with the cradle and having contact with those portions of the yarn wound on the bobbins which are adjacent the tips of the bobbins, and a tension spring one end of which is secured to the upper end of the member and the other end of which is secured in fixed position relatively to the frame of the magazine.

6. In a weft replenishing mechanism, means to guide a stack of bobbins, flexible means to engage those portions of the yarn on the bobbins adjacent the tips of the latter to prevent the final winds of yarn from unraveling, and means to move the flexible means out of engagement with the yarn on the bobbins.

7. In a weft replenishing mechanism, means to move a stack of bobbins toward transfer position one at a time, flexible means yieldingly mounted to engage those portions of the yarn on the bobbins adjacent the tips of the latter to prevent the final winds of yarn from unraveling, and mecha-

nism to move said flexible means out of engagement with the yarn on the bobbins when a bobbin moves toward transfer position.

8. In a weft replenishing mechanism, means defining a guide along which reserve bobbins move toward transfer position, flexible means presenting a substantially flat surface to engage those portions of the yarn

on the bobbins adjacent the tips of the latter to prevent the final winds of yarn from unraveling, and a device actuated by the replenishing mechanism to move the second named means away from the guide. 10

In testimony whereof I have hereunto affixed my signature.

ELMER JACOB.
